UNITED STATES PATENT OFFICE

103,150

DESIGN FOR A DISPLAY STAND

S. Charles Hirschberg, New York, N. Y.

Application November 21, 1936, Serial No. 66,076

Term of patent 7 years

To all whom it may concern:

Be it known that I, S. Charles Hirschberg, a citizen of the United States, residing at 1435 Lexington Avenue, New York city, in the county of New York, State of New York, have invented a new, original, and ornamental Design for Display Stands, of which the following is a specification, reference being had to the accompanying drawing forming part thereof.

In the drawing:

showing my new design, a portion of the base being shown broken away;

I claim:

The ornamental design for a display stand, as shown and described.

S. CHARLES HIRSCHBERG.
